(57) **CLAIM**

The ornamental design for an adjustable computer workstation, as shown and described.

DESCRIPTION

FIG. 1 is a perspective view of an adjustable computer workstation, showing our new design; FIG. 2 is a side elevational view in fully raised position; and, FIG. 3 is an elevational view showing the side not shown in FIG. 2 in fully lowered position.

The broken lines in FIGS. 1-3 are for environmental purposes only and form no part of the claimed design.

The rear of the article not shown is not part of the claimed design.
